UNITED STATES PATENT OFFICE.

WALTER B. SCOTT, OF MARBLEHEAD, MASSACHUSETTS.

DESIGN FOR A TOY WINDMILL.

Application filed June 15, 1925. Serial No. 13,786. Term of patent 14 years.

To all whom it may concern:

Be it known that I, WALTER B. SCOTT, a citizen of the United States, residing at Marblehead, in the county of Essex and State of Massachusetts, have invented a new, original, and ornamental Design for Toy Windmills, of which the following is a specification, reference being had to the accompanying drawing, forming part thereof.

Figure 1 is a side view of a toy wind mill;

Figure 2 is a top plan view of a toy wind mill;

Figure 3 is a perspective view of a toy wind mill, showing my new design.

I claim:

The ornamental design for a toy windmill, as shown.

WALTER B. SCOTT.
